UNITED STATES PATENT OFFICE.

FRANK ADAMAC, OF LAURELTON, NEW YORK, ASSIGNOR TO RUDOLPH FELIX, OF NEW YORK, N. Y., DOING BUSINESS AS THE OVALITE COMPANY.

DESIGN FOR A BASE FOR LAMPS OR THE LIKE.

Application filed May 16, 1924. Serial No. 9,628. Term of patent 3½ years.

To all whom it may concern:

Be it known that I, FRANK ADAMAC, a citizen of the United States, and a resident of Laurelton, county of Queens, and State of New York, have invented a new, original, and ornamental Design for a Base for Lamps or the like, of which the following is a specification, reference being had to the accompanying drawing, forming a part hereof.

The drawing shows a perspective view of the base for lamps or the like.

I claim:

The ornamental design for a base for lamps or the like substantially as shown.

FRANK ADAMAC.
